UNITED STATES PATENT OFFICE

2,009,339

SICKLE BAR FOR MOWING MACHINES

Joseph James Davis, Bethel, Vt.

Application September 29, 1933, Serial No. 691,547

1 Claim. (Cl. 56—300)

This invention relates to an improved reciprocating cutter or sickle bar such as is used in present day mowing and equivalent reaping and cutting machines.

Stated more explicitly the invented conception comprehends the provision of a scientifically correct properly balanced multiple tooth assemblage wherein the abutting teeth are detachably mounted on the supporting bar by efficient quick detachable means of a type and style calculated to permit selective removal, replacement and sharpening of damaged teeth.

Needless to say I am aware of the fact that it is not broadly new in this particular line of endeavor to detachably connect the cutter plates or teeth with the backing and supporting bar in a manner to expedite renewal and sharpening. Therefore, it is my principal aim to generally improve upon known patented and marketed arrangement through the adoption and use of a more systematic assemblage whose features of accommodation and adaptation transcend those of similar arrangements.

In carrying the principles of the present inventive idea into actual practice measures are taken to provide a more satisfactory, simplified and dependable construction devoid of superfluous details and characterized by requisite strength and durability in order to better fulfill the requirement of a construction of this class.

By way of introduction it is to be pointed out that in the aforesaid prior art devices acknowledged to be old it is generally necessary to resort to revision and changes in the fundamental details of the conventional style cutter bar. By way of contrast the improvement constituting the novelty of this invention provides an arrangement whose parts are aptly fitted to serve on the marketed type apertured cutter bar without requiring alterations in the stock parts, this being a logical and impressive refinement destined to be recognized as one of the principal improvements of the invention.

Other features and advantages will become more readily apparent from the following description and drawings.

In the drawings:—

Figure 1 is an elevational view of a structure developed in accordance with the principles and fundamentals of the present invention.

Figures 2, 3 and 4 are transverse sectional views taken on the planes of the lines 2—2, 3—3 and 4—4, respectively of Figure 1.

Figure 5 is an elevational view of one species

or variety of tooth or plate used in the improved assemblage.

Figures 6 and 7 are elevational views of other complementary and companion types of plates.

Figures 8 and 9 are detail elevational views of the especially fashioned retaining rivet used in perfecting the invention.

Referring now to Figure 1, I call attention to that part designated as a conventional casting or unit which comprises the usual type plate-like casting 10 having a ball joint connector 11 formed integral therewith to accommodate the pitman (not shown) or other actuating means commonly used in this type of machine. This casting also includes an extension 12 disposed in spaced parallelism with the adjacent end portion of the main supporting bar 13 for the various cutter plates or teeth. At the left hand end this bar 13 is riveted or otherwise secured to the main casting 10. As shown in Figure 3 special connecting pins or rivets are provided here, the rivets being formed with a flattened hemispherical head 14 on the side adjacent the bar 13 and a frustroconical head 15 on the casting side. The shank portion is enlarged as indicated at 16 to form a shoulder which bears against the bar 13 and which portion also serves as an anchor for the coordinated or complementary cutter plate. Incidentally the term "plate" and the term "teeth" are used in an equivalent sense to indicate the plate-like cutting elements.

As a matter of distinction between the three different sets of plates I desire to differentiate them as follows. There are two companion plates 17 at the left in Figure 1 located between the parts 10 and 13. At the extreme right hand end there is what may be designated as a master or key plate 18 and the ones between these plates 17 and 18 constitute the regular or standardized ones which are differentiated by the numerals 19. All of the plates 19 are of the same construction and the description of one will suffice for all. Considering first the plate 17 shown in Figure 5 it will be seen that it is of customary configuration so far as shape is concerned but provided in one side edge portion with a keeper notch 20 and in the rear edge portion with an L-shaped slot which may be described as a bayonet slot, the same including an entrance portion 21 and a seating branch 22 for cooperation with the portion 16 of the rivet. The terminal or end plate 18 shown in Figure 7 is the same in general outline but provided in one side edge with a keeper and guide notch 23 and in the opposite edge portion with a bolt hole

24. This is adapted to accommodate a bolt or permanent rivet 25 as shown in Figure 1 which must be removed to permit this plate 18 to be taken off and to allow the remaining plates 19 and 17 to be selectively removed or replaced as conditions require.

All of the plates 19 are the same in construction as shown in Figure 6, each plate is formed in the left hand side edge portion with a notch 26 opposite to which is a key-hole slot 27 and a clearance and assembling niche 28. It is to be pointed out that the rivet used to hold the plate 19 in place is somewhat similar to the one used to hold the plate 17 in position. One of these rivets is shown in Figure 9 and comprises a cylindrical shank 29 having a frusto-conical head 30 and an enlarged shoulder forming portion 31. The shoulder 31 bears against the attaching bar 13 as shown in Figure 4 and the shank 29 has its terminal portion shaped into a retaining head 32. The conical head 30 serves to hold the plate in position, said plate being supported on the shoulder part 31 between said head 30 and bar 13.

It is to be pointed out that the bar 13 as generally marketed is simply a longitudinally elongated member permanently riveted at the left hand end to the mounting or casting 10. At predetermined longitudinally spaced points it is provided with apertures to accommodate double headed rivets (not shown) which are used to hold similar cutting blades thereon. These plates are permanently held by the rivets and whenever one plate wears out and must be replaced it is necessary to file off the rivet and replace the plate with new rivets, etc. This is time consuming and inconvenient. For the present arrangement the plates 19 are easily held in place by the conical headed rivets of the style shown in Figure 9 in the manner illustrated in Figure 4. These rivets are allowed to remain permanently in place. By using the style of rivets which is shown in Figure 9, plates 19 can be applied to the conventional type of bar and securely anchored in place. Once in position said rivets are set to receive the interchangeable or renewable plates 19. Obviously it is easy to put one of these plates 19 into position by engaging the enlarged end of the keyhole slot over the head 30 and engaging the slot 26 with the next adjacent shank or rivet then sliding the plate from right to left. The clearance niches 28 facilitate this placement of the plates 19. In order to change

one of the plates 19 it is necessary to remove the master or key cutter plate 18 by taking out the bolt or rivet 25 as the case may be. The manner of inserting and removing the plates 17 is slightly different but is perfectly clear, it being simply necessary to angle the plate with respect to the supporting rivets so that they can be inserted between the two parts 10 and 13 and easily slipped into place.

Novelty is thought to reside in the provision of a mounting bar having the headed permanently attached shouldered rivets to accommodate the slotted plates 17, 18 and 19, particularly in conjunction with the single key forming plate 18 which is permanently held in its key position by a bolt or equivalent permanent fastener 25. When once this is removed the remaining plates can be easily removed and replaced as is obvious.

A careful consideration of the foregoing description in conjunction with the illustrative drawings will enable the reader to obtain a clear understanding of the purpose, features and advantages, the explicit construction, and the invention as hereinafter claimed.

It is to be understood that minor changes in shape, size, relative proportions, and materials may be resorted to in practice without departing from the spirit of the invention or the scope of the invention as now claimed.

What is claimed is:

In a sickle bar for mowing machines in which is comprised a reciprocatory bar, cutting plates arranged edgewise in series and superimposed flatwise on the bar, and means detachable from the outer end portion of the bar for normally holding said plates against edgewise movement, the combination with said reciprocatory bar and cutting plates, of rivets having shanks permanently secured in said bar at intervals in the length of the bar and also having enlarged shank portions bearing at their lower ends against the upper side of the bar, said enlarged shank portions disposed in the cutting plates and said plates disengageable from the rivets on edgewise movement of the plates after said first-named means is detached, and said rivets further having enlarged heads above said enlarged shank portions and arranged immediately above said cutting plates.

JOSEPH JAMES DAVIS.
